UNITED STATES PATENT OFFICE.

ISAAC W. FISHER, OF ESCONDIDO, CALIFORNIA.

CONCRETE FORM FOR LOG CABINS.

Application filed May 20, 1924. Serial No. 714,633.

To all whom it may concern:

Be it known that I, ISAAC W. FISHER, a citizen of the United States, residing at Escondido, in the county of San Diego and 5 State of California, have invented certain new and useful Improvements in Concrete Forms for Log Cabins; and I do hereby declare the following to be a full, clear, and exact description of the invention, such as will 10 enable others skilled in the art to which it app pertains to make and use the same.

The present invention relates to a frame or mold for forming a log cabin of concrete or analogous material, the mold being of sec 15 tional formation and adapted to be readily set up and easily taken apart after the structure has set.

Other objects and advantages will be apparent and suggest themselves as the nature 20 of the invention is understood.

While the drawings illustrate an embodiment of the invention it is to be understood that in adapting the same to meet different conditions and requirements, various changes 25 in the form, proportion and minor details of construction may be resorted to provided they fall within the spirit and scope of the invention as claimed.

Referring to the accompanying drawings 30 forming a part of the application:

Figure 1 is a horizontal sectional view of a concrete mold embodying the invention,

Figure 2 is a detail perspective view of a corner portion of the mold and structure,

Figure 3 is a diagrammatic view of a corner portion of the mold extended,

Figure 4 is a view similar to Figure 3 showing the reverse side of the parts,

Figure 5 is a detail sectional view on the 40 line 5—5 of Figure 1, and

Figure 6 is a detail sectional view on the line 6—6 of Figure 1.

Corresponding and like parts are referred to in the following description and designated in the several views of the drawings 45 by like reference characters.

It is to be understood that the general outline of the mold will depend upon the character of the structure to be formed and as 50 shown the frame comprises inner sections 10, outer sections 11 and corner sections 12 and 13. The inner sections 10 may consist of boards or plates which are retained in place by posts 14 which, as shown, are disposed at 55 the corners. The outer sections 11 are disposed opposite the respective inner sections

10 and are spaced therefrom a distance corresponding to the thickness of the walls of the structure. The faces of the sections may be of any form according to the required surface of the structure and in the present instance, the molding faces of the inner sections 10 are plane, whereas the molding faces of the outer sections 11 are longitudinally grooved or channeled to correspond with the appearance of the outer surface of a log cabin. Opposite outer sections 11 have end extensions 15 which are plain, the shoulder or abutment at the inner end of the extension 15 being notched as indicated at 16, said notches being half-round to correspond with one-half of the outer projections representing the ends of the logs beyond the notched joints. The other two outer sections 11 terminate in straight or square ends which abut 75 the adjacent corner sections 13. End strips 17 and 18 reinforce and strengthen the ends of the outer sections 11. The corner sections 12 and 13 are hingedly connected as indicated at 19, and the sections 12 are hinged to the 80 extensions 15 of the adjacent outer section 11, as indicated at 20, latches 21 being provided to secure the corner sections 13 to the reinforced ends of the adjacent outer section 11. The molding faces of the corner sections 12 and 13 are grooved or channeled to match the grooved or channeled faces of the outer sections in line therewith and their opposed edges are cut away and notched, as indicated at 22, to form projections corresponding to the projecting ends of logs, the projecting end on one side being formed between the notched edges 22 and the projecting ends at the opposite side being formed between the notched portion 16 of an outer 95 section 11 and the grooved face of the section 12 hinged thereto.

When the form is set up, a space is provided between the several sections and this space receives the concrete or other material from 100 which the structure is to be formed, said material being supplied to the space and tamped therein if necessary. After the material has set, the latches 21 are released thereby admitting of easy removal of the outer sections, 105 the inner sections being removable in any convenient and preferred way.

What is claimed is:

1. A mold for forming a structure of concrete, the same comprising spaced inner and 110 outer sections and corner sections, the latter being hingedly connected to one another and

to adjacent ends of the outer sections, and means detachably connecting the free edges of the corner sections to the free edges of the adjacent outer sections.

5 2. A mold for forming a structure of concrete, the same comprising inner and outer sections, corner sections hinged to one another and to the ends of adjacent outer sections, and latches connecting the free corner sections to the free edges of the adjacent outer sections.

10 3. A mold for forming a log cabin, the same comprising outer sections having their molding faces longitudinally grooved, one 15 of the sections having an extension and the shoulder thus formed notched, corner sections hinged to one another and to the ex-

tensions of the respective outer sections, the molding faces of the corner sections being grooved or channeled and their opposing edges being cut away and notched to form a projection corresponding to the projecting ends of logs, the other projecting ends of the logs being formed between the notched shoulder at the inner end of the extension and the 20 grooved face of the corner section hinged to said extension.

25 In testimony whereof I affix my signature in presence of two witnesses.

ISAAC W. FISHER.
